[57] **CLAIM**

The ornamental design for an auxiliary telephone cradle, as is shown and described.

DESCRIPTION

FIG. 1 is a top front perspective view of an auxiliary telephone cradle showing our new design;

FIG. 2 is a front elevation thereof;

FIG. 3 is a side elevation thereof; and

FIG. 4 is a top front perspective view thereof; the broken lines representing the fragmentary portion of a telephone unit being shown for illustrative purposes only.

FIG. 1

FIG. 2

FIG. 3

FIG. 4
